CLAIM

The ornamental design for a knife handle, as shown and described.

DESCRIPTION

FIG. 1 is a dimensional view of a knife handle showing my new design;

FIG. 2 is a front elevational view thereof, the rear elevational view being a mirror image;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a reference figure showing the tool in a state of use in combination with the design object.

The broken lines shown in the drawings are for illustrative purposes only and form no part of the claimed design.
